ART OF LINING UP PRINTED MATTER AND
REGISTERING TYPE

John P. Walsh, Boston, Mass.

Application March 23, 1935, Serial No. 12,625

6 Claims. (Cl. 33—184.5)

This invention relates to the printing art and more particularly to a combination lock-up and line-up frame for obtaining better printing at lower costs. Its purpose and use is to do away with lost time on printing presses caused by guesswork, when locking up forms on stone, making it necessary to line up sheet after taking impression from form, which keeps the press idle while the sheet is being lined up and moves are being made on the press.

Heretofore, the usual procedure has been to lock up the printing elements such as type, cuts or plates of various kinds in a chase on an imposing stone. The chase is then taken from the imposing stone to the printing press and locked on the bed of press. Under this practice it has been impossible to prepare the printing elements for the use of the press with any amount of accuracy and this results in wasted labor. The chase is then locked in the press and an impression or proof sheet taken. This impression is taken to the line-up table and checked for line-up and register. If the proof sheet shows that the type, cuts, or pages are out of alignment, then this work of lining up or positioning has to be done on bed of press and this results in keeping a press out of active duty for many hours. With my invention I do away with guess work on the imposing stone, and line up the printing elements as type, cuts, or plates in the correct position and eliminate the lost time that it takes to line up sheet on line-up table; also the time lost on presses due to inaccurate alignment.

The object of my invention is to eliminate much of this procedure without sacrifice of precision or accuracy of printing.

I accomplish this object by means of a novel piece of shop equipment which combines in a single piece of apparatus all of the advantages of the usual set-up and line-up tables when used separately while at the same time avoiding the disadvantages attendant upon the separate use of said tables as above pointed out.

My invention is a combination lock-up and line-up frame. In using it, the type is first accurately set for line-up and register by means of the special line-up and register devices with which my device is equipped.

With cheaper grades of printing or with rush printing it is unnecessary to take a proof of the set-up at all. Where more time is available or where unusually accurate printing is required, my combination lock-up and line-up frame makes it possible to take an impression or proof and check the same for accuracy of line-up and

register without the necessity of removing the lock-up frame from the imposing stone so that if errors appear these may be corrected by re-setting the type in the lock up frame without taking the lock-up frame from the imposing stone.

Other advantages are that my combination lock-up and line-up frame conserves space in the printing shop, eliminating as it does the necessity for having either a set-up table or a line-up table, saves the wages of the craftsman ordinarily employed at the table eliminated, saves time in filling any printing order, and avoids keeping the press idle while the sheet is being lined-up and corrections made.

My combination lock-up frame may be attached to any imposing stone, or may be used for lining up sheets or marking up layouts in the same manner that the ordinary line-up table is used.

Structurally, my lock-up frame comprises a one-piece frame graduated on all sides and provided with a removable bottom bar to permit the chase or form to slide in and out easily. Straight edges are mounted to traverse the frame longitudinally and transversely so that the form can be made up sideways as well as up and down at the same time and these straight edges are graduated and readable with reference to the graduated sides of the frame.

As illustrative of the principles of my invention I show in the accompanying drawings an embodiment of my invention which I have found highly satisfactory under actual service conditions and well adapted to the requirements of commercial manufacture.

In such drawings:—

Fig. 1 is a perspective view of a lock-up frame embodying my invention in place on the imposing stone of an imposing table, and illustrating the manner of lining and squaring up the printing elements in the desired arrangements and also showing how two or more straight edges can be used at any time when lining up the form.

Fig. 2 is a fragmentary perspective of one of the gear racks on which the straight edges run and also shows the gibs above the rack which prevent any side play and insuring accuracy as well as one of the adjusting screws for adjusting the gear racks.

Fig. 3 shows in full and dotted lines one straight edge which can be used in both directions and the thumb lock screw which makes it possible to tip straight edges back so that the stoneman can make adjustment without losing his first adjustment, such straight edges being graduated and

readable with reference to the graduations of the lock-up frame, and being provided with sliding printer's scales.

Fig. 4 shows a modification of the straight edge 5 shown in Fig. 3 wherein the straight edge is carried by a sliding frame instead of a geared one.

Fig. 5 shows my lock-up frame being used for marking out and getting position on paper, this being done by placing mark-out board inside 10 frame in place of form, and also shows the impression roller which is used when taking an impression from the form and which enables the stone-man to get a printed impression from the imposing stone without lifting the form onto the 15 printing press.

Fig. 5a is a fragmentary detail showing a type high gauge which may be used in connection with my invention.

Fig. 6 is a fragmentary perspective showing 20 mark-out board and a spring clamp which may be used in connection with my invention.

Fig. 7 is a cross-section showing one of the 25 spring fingers on the mark-out board closed to clamp the paper to the board.

Fig. 8 is a similar view showing said finger opened so that the paper may be placed in position on the mark-out board.

Fig. 9 shows an imposing stone cabinet with my lock-up frame being used to line up sheet of 30 paper on the mark-out board and also shows the impression roller out of the way when not being used and the small hand inking roller and ink slab for inking said impression roller.

Fig. 10 is a similar view showing my lock-up 35 frame being used with mark-out or lining up board, together with adjustable position guides which are used when striking in two or more colors and register rods used to register forms, and

Fig. 11 is a detail of one of such register rods.

Referring now in detail to the embodiment of the invention illustrated in the drawings I have indicated at 13 the top of an imposing stone and generally at 14 my novel lock-up frame which is 40 doweled or otherwise fastened as at 15 on all sides to the top of the imposing stone making it one solid frame. The printer's chase or form 16 is locked inside of the frame 14 by means of printers' quoins 17 (Fig. 10) to keep the same rigid 45 and in a definite position on top of imposing stone.

The type, cuts, plates or other printing elements 18 are placed inside of the chase or form 16 and lined up and positioned by means of the 50 pair of straight edges 19 and 19' which move respectively longitudinally and transversely of the chase or form 16 on pinions 20 which run in racks 21. The straight edges are placed in the desired position on frame 14 and type, cuts or other printing matter can be brought up to them for proper line-up and position. The straight edges are graduated on both ends and carry sliding 55 printer's scales 27 which make it possible to line-up and space accurately in both directions at the same time.

After the type, cuts, or form are lined-up and locked in the chase 16, a proof or impression may be taken from the form by means of the impression roll 24 shown in Fig. 9. This is done by means of the ink roller 25 which gets ink from the ink slab 26 and is then rolled over the type or form to ink the same, after which a sheet of paper is placed on top of type or form and the impression roll 24 is run over the sheet giving a 60

good clear impression. Position, line-up and register can be made from this proof sheet and corrections can be made before removing the lock-up frame and placing it in the printing press.

The lock-up frame 14 is graduated on all four sides, as indicated at 14' and the graduations of the longitudinal and transverse straight edges 19 and 19' are readable with reference to such graduations.

The racks 21 for the pinions of the longitudinally sliding straight edge 19 are located in the side rails of the lock-up frame, and those for the transversely sliding straight-edge 19' are located in the end rails of the lock-up frame.

The several rack holders or frame rails are gibbed as at 40 and arranged (Fig. 2) to prevent any side play, and two of the racks are provided with adjustment screws 23 which pull against the shoulders 23' or push against the surfaces 23a to adjust the racks. By turning the thumb screw 23, the rack is adjusted, and in such adjustment adjusts the printers' scale 27 which it carries. The shafts which carry the straight edges and their pinions may be provided with handles or knobs 41 (Fig. 1) by means of which the straight edges may be conveniently moved back and forth over the chase or form 16.

The impression roller 24 preferably runs in the same racks in which the straight edge 19 runs, 30 being provided with pinions 42 (Fig. 9) meshing in said racks, and with an extended manipulating handle or its equivalent 43.

One or both straight edges may be mounted for rocking movement relative to the chase or 35 form. (See Fig. 3.) When so mounted, the straight edge is provided with a thumb lock screw 22 adapted to be set against the pinion shaft 44 to lock the straight edge from rolling along the rack. By tipping the straight edge to 40 the dotted line position shown in Fig. 3 it is possible for the stone-man to make a second adjustment without losing his first adjustment of the straight edge.

In the modification shown in Fig. 4 the straight edge is carried by a sliding frame 45 instead of a rack and pinion arrangement as in Fig. 1.

The lock-up frame has a removable bottom bar 46 (Fig. 5) which slides laterally into and out of the frame at one side thereof in suitable grooves 47 and locks the chase or form 16 within the frame. By withdrawing said bar laterally as shown in Fig. 5, the chase or form 16 may be slid out of the frame when ready to be taken to the printing press. When so constructed, the frame rail and rack at this side of the lock-up frame is made in three sections, viz, the removable center section 46 and the fixed end sections 14a. The fixed sections 14a are permanently fastened by means of the screws 33 to the end rails 14 of the lock-up frame. The removable section 14 is detachably fastened to said end rails by the screws 33a, so that by withdrawing said screws 33a the section 46 may be slid laterally outward into the position of Fig. 5.

Where used to mark lay-outs, plot out work and the like, I replace the chase or form with a mark-out board 48 (Fig. 5) inside the lock-up frame, and clamp the sheet 49 to be marked in position upon said board by means of spring hold-down fingers 50 (Figs. 6, 7 and 8).

These are fastened as at 51 in recesses formed in an edge bar 52 which overlies a cam bar 53. The cam bar 53 is mounted in a longitudinal recess 54 formed in one of the side walls of the 75

mark-up board and provided with a cam surface 55 against which the bar 53 cams when the bar is turned on its axis to open the spring fingers 50 as shown in Fig. 1. The cam bar 53 is provided with a handle 56 by which it may be conveniently operated, and pushes against cams 57 formed on the under sides of the spring fingers 50 when turned on its axis to open said fingers.

10 In Fig. 9 I have shown my lock-up frame in position upon an imposing table or cabinet 58 and being used to line up a sheet of paper clamped to the mark-out board.

In Fig. 10 I have shown in connection with 15 my lock-up frame certain position guides 28 which are used when striking in two or more colors.

These guides are adjustable to any position 20 along the rods 29 on which they are slidably mounted such adjustment being permitted and held by means of set screws 30. The fingers 28' are adjustable inwardly and outwardly over the paper sheet by means of adjustment screws 30'.

The guides 28 are removable when not needed, 25 and are ordinarily used only when striking in the second form.

In Fig. 10 also, I show the front bar 32 of the frame hinged as at 31 to the imposing stone 13. This enables the front bar to be lifted and 30 turned to lie below the surface of the imposing stone so that the chase or form may be slid on or off the imposing stone. When the front bar 32 of the frame is turned back into place, it is fastened to the frame by means of the set 35 screws 33a.

In Fig. 10 and also in Fig. 11 I show an adjustable register rod 34 carried by one of the position guides 28. This is used in registering forms. Its adjustment is held by means of the 40 set screw 35.

In Fig. 5a, I show a type high gauge 60 which may be used in connection with my invention. The type to be gauged is slipped into the recess afforded by the bent end of said gauge and is 45 gauged for correct height between the opposing surfaces 61 and 62 of said bent end. The gauge itself is fastened as at 63 to one of the rails of the lock-up frame.

What I therefore claim and desire to secure 50 by Letters Patent is:

1. A combination lock-up and line-up frame for use in lining and squaring up printing elements in a chase on an imposing stone without removing either the chase or the frame from the 55 imposing stone, comprising graduated rails adapted to be assembled as a frame and fastened to the imposing stone in enclosing relation to the chase, a double-edged straight edge member mounted on said frame for both sliding and tilt-

ing movements relative to the chase and provided with graduations along both of its edges which are readable with reference to the graduations of the frame rails accordingly as said straight edge member is tilted to bring a selected edge thereof into juxtaposition to the chase, and means for releasably locking the straight edge member in tilted position without interfering with the sliding movements thereof over the chase.

2. A combination lock-up and line-up frame 10 for use in lining and squaring up printing elements in a chase on an imposing stone without removing either the chase or the frame from the imposing stone, comprising graduated rails adapted to be assembled as a frame and fastened 15 to the imposing stone in enclosing relation to the chase, certain of said rails being provided with racks, a double-edged straight edge member mounted on said frame for both sliding and tilting movements relative to the chase, said 20 straight-edge member being provided with shaft carrying pinions meshing with said racks, and both edges of said straight-edge member being provided with graduations which are readable with reference to the graduations of the frame 25 rails accordingly as said straight edge member is tilted to bring a selected edge thereof into juxtaposition to the chase, and means for releasably locking the straight edge member in tilted position without interfering with the sliding movements thereof over the chase.

3. The device of claim 2, said locking means comprising a set screw disposed through said 30 straight-edge member and engageable with said pinion shaft.

4. A combination lay-out and line-up device for use in marking out lay-outs on a work sheet laid on a mark-out board, comprising a frame having graduated rails including a removable section, a mark-out board positioned within said frame and 40 removably clamped therein by said removable frame section, work-sheet clamping means carried by said removable frame section for clamping the work-sheet to said mark-out board, and a straight edge member mounted on said frame 45 for traversing movements over the work sheet and provided with graduations readable with reference to the graduations of the frame rails.

5. The device of claim 4, the work-sheet clamping means comprising spring hold-down fingers, 50 and cam means for opening and closing said fingers.

6. The device of claim 4, the work-sheet clamping means comprising spring hold-down fingers, an edge bar to which the outer ends of said 55 fingers are connected, and a cam bar coacting with said edge bar for opening and closing said fingers.

JOHN P. WALSH.
